(57) **CLAIM**

The ornamental design for a flatulence novelty toy, as shown and described.

DESCRIPTION

FIG. 1 is a front, top perspective view of the flatulence novelty toy.

FIG. 2 is a front elevation view thereof.

FIG. 3 is a rear elevation view thereof.

FIG. 4 is a left side elevation thereof, the right-side view being a mirror image thereof.

FIG. 5 is a top plan view thereof; and,

FIG. 6 is a bottom plan view thereof.

The broken lines shown in the drawings illustrate portions of the flatulence novelty toy that form no part of the claimed design.

1 Claim, 3 Drawing Sheets
